Application February 4, 1938, Serial No. 188,765
In Germany February 8, 1937

3 Claims. (Cl. 250—27.5)

This invention relates to gaseous discharge tubes, and more particularly to ionic relay tubes having a grid to control the discharge.

By gaseous discharge tube is means a tube 5 whose filling comprises one or more gases or vapors, or a mixture thereof.

In such tubes the electrodes are so proportioned and interspaced with respect to the pressure of the gaseous filling, that the discharge can be 10 interrupted without reducing the anode voltage to zero or to a small value. This effect is generally a function of the anode voltage applied to the tube and of the amount of anode current flowing at the time of interruption, and the tube 15 is so designed that the positive ion sheaths occurring at adjacent portions of the negatively-charged control grid contact with each other and with the electrons of the discharge passing through the grid aperture in question. As a result, the passage of discharge current at this 20 point is completely interrupted.

In the past such an interruption of the discharge could be insured only with very low discharge currents, and with grids having very 25 small apertures. More particularly, as the thickness of the positive ion sheath is determined by the degree of ionization of the plasma in the apertures of the grid, the positive ion sheath becomes thinner with a high concentration of the 30 discharge in the grid aperture, and as a result only discharge currents of very low intensity can be interrupted. This difficulty is very pronounced when the discharge concentrates upon a single 35 aperture of the grid so that the remaining apertures are inoperative.

It is well known that when an arc-discharge issues from an incandescent cathode in a gaseous filling at a comparatively low pressure, for instance from a few microns to several millimetres 40 of mercury, there is formed in the immediate vicinity of the cathode a comparatively thin cathodic dark discharge space which absorbs substantially the entire voltage drop of the discharge. The thickness of this dark space in centimetres 45 can be determined approximately from the following formula:

$$d = 2.08 \times 10^{-3} \times V_a 3/4 \times i^{-1/2} \quad (1)$$

in which i is the current density in amperes per 50 square centimeters of the discharge at the cathode surface, and V_a is the cathodic voltage drop. For pressures less than 10 millimeters of mercury, Formula 1 is substantially independent of the pressure of the filling, and although it ignores the influence of cathode curvature, this is

permissible provided the thickness of the dark discharge space is very small relative to the radius of curvature of the cathode surface, which is usually the case in practice.

From Formula 1 we may obtain the following simple Formula 2 for the maximum thickness (d_{max}) of the normal cathodic dark discharge space, when there are no other electrodes in the immediate vicinity of the cathode, since 17 volts may be inserted as the maximum value that may be expected for V_a .

$$d_{max} = \frac{1.74 \times 10^{-2}}{i^{1/2}} \quad (2)$$

Experiments have shown that this cathodic dark space must extend to the grid which is interposed between the cathode and anode, and must completely fill the intermediate space in order that the discharge may be interrupted by this grid. This small thickness of the cathodic dark space has caused considerable difficulties in the manufacture of such tubes, because the small distance between the grid and cathode made it very difficult to prevent inadmissible heating of the grid, and it was also difficult to obtain and maintain a well-insulated arrangement.

We have found that a very favorable grid action can be obtained, even when the grid is arranged beyond the range of the normal dark discharge space, and that under the influence of a neighboring electrode the cathode dark space can—within certain limits—be drawn beyond its normal thickness and into the proximity of this electrode. For this purpose and in accordance with the invention, we so locate the grid that it separates the cathode from the anode, and that its distance from the cathode exceeds the above-defined maximum thickness (d_{max}) of the normal cathodic dark space, but is sufficiently small to allow the cathodic dark space—which in this case will extend a greater distance from the cathode—to completely fill the portion of the discharge space between the grid and the cathode.

The above results may be obtained conveniently by using a grid of wire mesh whose apertures have a maximum width of about 0.4 mm., and by using an argon filling having a pressure during operation of not more than 0.7 mm. of mercury, or a filling of another rare gas, vapor or mixture thereof at such pressure that an aqual free path of the atoms is obtained.

A particularly advantageous electrode arrangement is obtained when using a grid-cathode distance of 2 to 4 mm.

From Formula 2 above, we find the following

values for the maximum thickness ($d_{\max}$) of the cathodic dark space as a function of the discharge current density i at the cathode surface:

Table I

5

	$d_{\max}$ (mm.)	i (amps. per sq. cm.)
10	0.12	2
	0.18	1
	0.38	0.2
	0.55	0.1
	0.85	0.005

From Table I it appears that $d_{\max}$ does not reach 1 mm. even with the lowest surface loads of the cathode. Thus the increase that may be obtained according to the invention in the grid-cathode distance is of the greatest importance because this increase enables one to prevent excess heating of the grid and insulation difficulties. Notwithstanding this increase in grid-cathode distance, the space between the grid and the cathode can be completely filled up by the cathodic dark space. Furthermore, concentration of the discharge upon a part of the grid or cathode surface—which is possible with the usual construction and effects interruption of the discharge—is eliminated, and as a result within certain limits the discharge can be interrupted independently of the anode voltage or anode current.

In order that the invention may be more clearly understood and readily carried into effect, we shall describe the same in more detail with reference to the accompanying drawing, in which the single figure is a sectionized view of an ionic relay tube according to the invention.

The tube illustrated in the drawing comprises a glass envelope 1 having a pinch 6. Supported from the pinch 6 by a lead-support 8 is an indirectly-heated cathode body 2 whose outer surface is provided with a suitable electron-emissive substance, and a heating element 3 having leads 9 and 10. Insulated from cathode 2 by means of two rings 7 of insulating material such as magnesia and disposed a short distance therefrom, is a cylindrical grid 4 of wire mesh provided with a lead 11. Located at a relatively large distance from the grid 4 and supported from pinch 6 by lead supports 12 are two plate-shaped anodes 5.

In the portion of the discharge space between the cathode 2 and the grid 4 there are no points at which the distance between the grid and cathode exceeds the values which are admissible according to the invention. If a larger distance did exist, even at a single point, so that the cathodic dark space did not extend to the grid, it would no longer be possible to insure an accurate extinguishing effect under all conditions.

60 Experiments were made with tubes of the type illustrated, in which the anodes 5 were electrically connected to a suitable current supply source. Cathode 2 had an active length of 23 mm., a diameter of 4 mm., and an active surface of 2.9 sq. cms., and grid 4 consisted of a metal wire mesh. We have made several tubes according to the above data, with different distances d between the cathode 2 and grid 4, with an argon filling at different pressures, and with different 70 size grid mesh.

As a result of such tests the data given in the following tables was obtained: Table II gives the maximum values of current that could be readily extinguished with different distances between the grid and cathode, when the tube had a filling

of argon at a pressure of 0.3 mm. of mercury during operation and with a grid mesh of 230.

Table II

5

Grid-cathode distance (mm.)	Discharge current (mA)
4.0	100
1.5	200
0.35	2500

With tubes having a grid-cathode distance of 1.5 mm. and a grid mesh of 230μ , the maximum current that could be interrupted varied with the pressure of the filling as follows:

Table III

20

Argon pressure (mm. of Hg.)	Current (mA)
0.5	100
0.3	200
0.1	1500

With the same grid-cathode distance as in Table III, and with an argon filling at a pressure of 0.1 mm. of mercury, the influence of the mesh-width was as follows:

Table IV

30

Mesh width (microns)	Current (mA)
230	1500
500	50

All the above results were obtained with the circuit represented in the drawing. Said circuit comprises a D. C.-supply 13 the positive terminal of which is connected through a D. C.-load 14, and an equalizing resistance 15, to the anodes 5 of the tube. The negative terminal of the D. C.-supply 13 is connected to the cathode 2, thus completing the main discharge circuit traversing the tube. A second D. C.-supply 16 is connected, with its positive terminal to the cathode 2, its negative terminal being connected, through a limiting resistance 17, to a switching key 18, the condenser 19 being permanently kept at the potential of the D. C.-supply 16. As soon as the key is depressed, the condenser communicates a negative impulse to the grid 4, thus interrupting the main discharge from the anodes 5, against the full pressure of the D. C.-supply 13. The lead-in conductor 9 of the heater 3 is directly connected to the cathode lead, whereas the lead-in conductor 10 is connected, through the limiting resistance 20, to the positive terminal of the D. C.-supply 13.

The experiments described above have been executed with a voltage of the D. C.-supply 13 of about hundred volts and it proved possible to reliably interrupt the arc by means of a condenser 19 of $2\mu\text{F}$, the voltage of the D. C.-supply 16 ranging between from 20-50 volts. The same result may be obtained by replacing the condenser 19 by a supply of constant D. C.-potential, e. g. a battery, of 1-3 volts, so as to impart to the grid a negative voltage of that value with respect to the cathode.

Even when using a directly-heated helical cathode, a grid-cathode distance of about 0.9 mm., an argon filling at a pressure of 0.3 mm. of Hg and a mesh-width of about 230 microns, an-

ode currents of 500 mA. can be interrupted in a reliable manner.

While we have described our invention in connection with specific examples and applications, we do not wish to be limited thereto but desire the appended claims to be construed as broadly as permissible in view of the prior art.

What we claim is:

1. An ionic relay tube comprising an envelope, 10 an anode and a cathode within said envelope and spaced apart to form a discharge space, a gaseous filling, and an apertured extinguishing grid adapted to be negatively charged between said anode and cathode and disposed from the cathode 15 a distance materially greater than the maximum thickness d_{max} of the normal cathodic dark space, the distance d_{max} equaling

$$\frac{1.74 \times 10^{-2}}{i^{1/2}}$$

20 cms. in which i is the current density in amperes per sq. cm. of the discharge at the cathode surface, the cathodic dark space of the tube extending with its outer limits reaching the openings 25 of said grid at the values of operating current density of the tube and completely filling the portion of the discharge space between said cathode and grid.

2. An ionic relay tube comprising an envelope, 30 an anode and a cathode within said envelope and spaced apart to form a discharge space, a

filling of argon having a maximum pressure during operation of 0.7 mm. of Hg., and an extinguishing grid adapted to be negatively charged disposed between said anode and cathode and comprising wire mesh provided with apertures having a width less than 0.4 mm., said grid being spaced from said cathode a distance greater than the maximum thickness d_{max} of the normal cathodic dark space, the distance d_{max} equaling

$$\frac{1.74 \times 10^{-2}}{i^{1/2}}$$

15 cms. in which i is the current density of the discharge at the surface of the cathode in amperes per sq. cm., the cathodic dark space of the tube extending into the openings in the wire mesh at the values of current density for which the tube is designed.

3. An ionic relay tube comprising an envelope, 20 an anode and a cathode within said envelope and spaced apart to form a discharge space, a gaseous filling within said envelope, and an apertured extinguishing electrode adapted to be negatively charged and separating said anode and cathode and spaced from said cathode by a distance of from 2 to 4 mm., the cathodic dark space of the tube extending with its outer limit reaching the apertures of said grid at the values of current density for which said tube is designed.
